UNITED STATES PATENT OFFICE.

EDWARD P. LYNCH, OF SALT LAKE CITY, UTAH, ASSIGNOR TO THE AULTMAN COMPANY, OF CANTON, OHIO.

ROAD-SCRAPER.

SPECIFICATION forming part of Letters Patent No. 674,703, dated May 21, 1901.

Application filed December 18, 1897. Serial No. 662,419. (No model.)

To all whom it may concern:

Be it known that I, EDWARD P. LYNCH, a citizen of the United States, residing at Salt Lake City, in the county of Salt Lake and 5 State of Utah, have invented certain new and useful Improvements in Road-Scrapers; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

15 Figure 1 is a side elevation of a road-scraping machine embodying my invention. Fig. 2 is a plan view. Fig. 3 is a plan view of some of the details enlarged. Fig. 4 is a section on the line $x-x$, Fig. 3. Fig. 5 is a section on 20 the line $y-y$, Fig. 3.

Inasmuch as the parts embodying the present invention can be applied to any of several forms of mechanism, it will not be necessary here to describe in detail all of the parts 25 of the machine shown.

The operative parts of the machine are supported upon a main frame, the principal elements of which consist of longitudinal bars A A', having a front upwardly-extending part a , 30 an approximately horizontal portion a' , and a rear inclined part a^2 . This main frame is supported upon a running-gear comprising a front axle C, with wheels D, and a rear axle C', with wheels D'. The front axle is pivotally connected with the front part of the main frame in any approved manner. Over or 35 near the main axle there is arranged the platform or support B, upon which the operator stands and from which he can reach the various levers and hand-wheels by which the 40 operative parts are controlled.

Upon the supporting and carrying devices above referred to is arranged the scraper-blade E. This also may be of the common 45 forms or any preferred sort. It is connected by horizontal pivoting devices to draft-bars E', which, as shown, are curved downward and are secured to the rear side of the scraper-blade and extended forward over the top 50 thereof to the part which carries them. The

latter is indicated by F and consists of an expanded ring-like plate, to which the aforesaid bars or arms E' are bolted. This ring or plate F is capable of rotation or adjustment around a vertical axis. To permit this, it 55 may be held in any suitable way, as by clips or flanged bolts G, secured to the draft-frame of the scraper, consisting of one or more bars I, which are pivotally connected to the main frame at the front ends, and one or more 60 cross-bars I'.

The draft-frame and the scraper-carrier can be readily adjusted vertically either at one side or the other, or on both sides simultaneously, by means of any suitable lifting mechanism, either such as indicated or any other that is preferred.

From what has been stated it will be seen that the scraper is capable of any of the adjustments ordinarily incident to these devices.

The present invention relates to the mechanism for effecting the rotation of the scraper ring or plate F or its adjustment around its vertical axis. To accomplish this, a series 75 of gear-teeth J are formed along the inner edge of the ring, they being concentric with its axis and of a number sufficient to permit as wide a range of adjustment as is desired. With this series of teeth a wheel K is arranged 80 to engage. It is carried loosely by a shaft k, which is mounted loosely in bearings l, formed in a bracket, (indicated as a whole by L,) which is bolted to the draft-bars I I', said shaft being adapted to slide more or less in its bearings. At k' the shaft is squared, and when it is pushed longitudinally far enough to have the square part within the pinion K the latter can be rotated, it having a square aperture to engage with this part of the shaft; 85 but normally the pinion is loose upon the shaft. The ring or circle plate F is also provided with a series of apertures f, and with these a locking pin or bolt M can engage. This locking-bolt is carried by a link or bar 95 N, pivoted at n to the bracket or lock-frame L. The link or bar N can be raised when desired by means of a cam O on the shaft k, any suitable connecting device between the cam and the link being interposed—as, for 100

instance, a hinged finger or arm O' . This finger or arm O' in the embodiment of the invention here illustrated is pivotally connected to the link N and extends downwardly therefrom through a guide O^2 . A spring T acts to normally draw the bar O' downward and also the lock pin or bolt M . When it is desired to lift the lock-bolt, the shaft k is pushed endwise far enough to bring the cam O under the trip-arm O' and into the position shown in Fig. 5, and then the shaft is turned in such way as to cause the cam to lift the pin out of the aperture f in the scraper-ring. After that has been accomplished the shaft is pushed longitudinally a short distance farther in order to bring the square part k' into the square aperture in the pinion K . Then the latter can be rotated, and the ring and scraper can be thereby adjusted as desired. After the adjustment is effected the shaft is drawn backward again to disengage it from the pinion K and so adjusted that the arm or finger O' is allowed to escape from the cam O , whereupon the spring P tends to draw the lock-bolt M down into engagement with the scraper-circle.

If the pin should fail to register with one of the apertures f , the ring can be slightly turned in either direction to bring one of the apertures to the pin by means of the clutch-teeth Q , carried by the shaft and adapted to engage with clutch-sockets q on the forward face of the pinion K .

In order to prevent the loosely-mounted pinion from being displaced by the endwise movements of the shaft, I employ a retaining finger or plate R , so situated as to bear against the inner face of the wheel, but which permits its rotating freely.

It will be seen that with a mechanism embodying the characteristic features of the parts above described I am enabled to dispense with one of the elements that has been found necessary in machines of this class as heretofore constructed, that element being a special hand-lever or foot-lever with flexible shafting formed in several sections united with sliding and tumbling rod joints for operating the pin or bolt. With the present device I am enabled to not only perform the work of adjusting the scraper, but also of fastening it after adjustment by a single power-transmitting element, such as the hand-wheel and shaft extending from the operator's platform to the pinion and lock.

It will be seen that numerous modifications can be made without departing from the essential features of the invention, and I therefore do not limit myself exactly to the details which I have shown, they being those which I at present prefer and which I here employ for illustration, but from which there can be departure in many respects.

What I claim is—

1. In a machine of the class described the combination with the adjustable scraper, the means for adjusting it, and the lock, entirely

independent of the said adjusting means, for holding the scraper after adjustment, of a power-transmitting device adapted to actuate both the lock and the adjusting means, substantially as set forth. 70

2. In a machine of the class described the combination of the scraper adjustable around a vertical axis, the toothed gearing for effecting its adjustment, the lock entirely independent of said gearing for positively holding the scraper after adjustment, the shaft adapted to be actuated from the operator's support and arranged to alternately actuate the adjusting-gearing and the lock, substantially as set forth. 75

3. In a machine of the class described, the combination of the main frame, having an operator's support, a draft-frame connected with the main frame and adjustable relative thereto both vertically and horizontally, the scraper, a carrier for the scraper mounted upon the draft-frame, and adjustable about an axis, means for effecting the adjustment of the said scraper and its carrier, a lock for positively holding the scraper and its carrier after adjustment, and a power-transmitting device arranged to actuate both the lock and the said adjusting means, and extending from the draft-frame to the main frame adjacent to the operator's support, whereby it is accessible to the operator upon the support whatever may be the adjustment of the draft-frame, substantially as set forth. 80 90

4. In a machine of the class described, the combination of the scraper, means for adjusting it comprising a toothed pinion or wheel, a lock for holding the scraper after it has been adjusted, and a shaft upon which the said pinion is loosely mounted, provided with means for engaging with and turning the said pinion or wheel, and also with means for operating the lock, substantially as set forth. 95 100

5. In a machine of the class described, the combination of the adjustable scraper, means for adjusting it, an automatically-operating lock for holding the scraper after adjustment, and a power-transmitting device for actuating the means for adjusting the scraper, and provided with means for releasing the scraper from the lock, substantially as set forth. 110 115

6. In a road-scraping machine, the combination of the main frame provided with an operator's support, a draft-frame connected thereto and adjustable both vertically and horizontally, a scraper, a scraper-carrier supported upon the draft-frame and adjustable about an axis to effect the angular adjustment of the scraper, a lock for holding the scraper in position after it has been angularly adjusted, gearing for moving the scraper-carrier to effect its angular adjustment, and shafting, supported on the main frame and adjacent to the operator's support, and also upon the draft-frame, the said shafting being arranged to operate both the lock and the angular adjusting means for the scraper, substantially as set forth. 120 125 130

7. In a road-scraping machine, the combination of a scraper, a support or carrier therefor, capable of angular adjustment, gearing for effecting such angular adjustment, a lock for holding the scraper in position after adjustment, and a single power-transmitting device provided with means for operating the lock and the gearing for adjusting the scraper, the said means being movable relative to these parts, whereby it may be engaged with either one or the other of them, or disengage from both of them at the will of the operator, substantially as set forth.
8. In a road-scraping machine the combination with the scraper, the means for adjusting it and the lock for holding it after adjustment, of a shaft adapted to slide relatively to both the lock and the adjusting mechanism and to actuate them both, substantially as set forth.
9. In a machine of the class described, the combination with the scraper, means for adjusting the scraper, and a lock independent of the adjusting device and adapted to hold the scraper in its adjusted position, of a power-transmitting device adapted both to release the lock and actuate the adjusting device, substantially as described.
10. In a road-scraping machine, the combination of a frame, an operator's platform thereon, a scraper adjustably supported on said frame, a lock-pin movable toward and from the scraper-support, and adapted to lock the same rigidly to the frame, means for moving said pin out of engagement with the scraper, a shaft for actuating said means extending to the operator's platform, and means adapted to be detachably engaged by said shaft for adjusting the scraper, substantially as set forth.
11. In a road-scraping machine, the combination of a frame, an operator's platform thereon, the scraper adjustably supported on said frame, a rack connected with the scraper, a spring-actuated lock for holding the scraper stationary, a shaft, means mounted on the shaft for moving the lock out of engagement with the scraper, a pinion meshing with the aforesaid rack, and adapted to be engaged with said shaft, and means accessible from the operator's platform for actuating the shaft, substantially as set forth.
12. In a road-scraping machine the combination of the adjustable scraper, the lock, the adjusting mechanism, two alternately-acting actuating devices for the adjusting mechanism and a shaft for operating both of the actuating devices, substantially as set forth.
13. In a road-scraping machine the combination of the adjustable scraper, the lock, the adjusting gear-wheel, the shaft, and two alternately-acting clutch-like devices for connecting the shaft to the gear-wheel, substantially as set forth.
14. In a road-scraping machine the combination of the adjustable scraper, the lock, the adjusting mechanism, a shaft, the two clutch-like devices between the shaft and the adjusting mechanism and means for connecting the shaft with the lock, substantially as set forth.
15. In a road-scraping machine the combination of the adjustable scraper, the main frame, the operator's support, a lock-pin, or equivalent for holding the scraper, means for adjusting the scraper when the lock is open, a shaft adapted to actuate either the lock or the adjusting mechanism, and means accessible to the operator when on the platform for sliding said shaft relatively to the lock and said adjusting mechanism, substantially as set forth.
16. In a road-scraping machine the combination of the adjustable scraper, the scraper-carrier, the adjusting-wheel, the sliding shaft, means to prevent displacement of the wheel, the lock, the cam actuated by the shaft for opening the lock, and a clutch-like device for connecting the shaft with the wheel, substantially as set forth.
17. In a road-scraping machine, the combination of an adjustable scraper, a lock for holding the scraper stationary, gearing for varying the position of the scraper, a power-shaft, means controlled by said shaft for releasing said lock, means for connecting said shaft with one member of the scraper-adjusting gearing when the lock-releasing devices are in an inoperative position, and independent means for connecting said shaft and gearing when the lock-releasing devices are in operative position, substantially as set forth.
18. In a road-scraping machine, the combination of the supporting-frame, a scraper and its carrier supported thereby, arranged to be angularly adjusted, a rack and pinion for effecting the angular adjustment of the scraper and its support, locking means for holding the scraper and its support in the positions to which they are adjusted, a longitudinally-movable shaft upon which is supported the pinion constituting part of the means for angularly adjusting the scraper, and means also supported by the said shaft and movable therewith, arranged to be brought into engagement with and to operate the said locking means, substantially as set forth.
- In testimony whereof I affix my signature in presence of two witnesses.
